PERCY OLIVER OTT, OF ROCKFORD, ILLINOIS, ASSIGNOR TO RACINE TOOL & MACHINE COMPANY, OF RACINE, WISCONSIN, A CORPORATION OF WISCONSIN

HYDRAULIC PUMP

Application filed July 25, 1929. Serial No. 380,939.

The invention relates to hydraulic pumps. The general object of the invention is to provide a rotary type hydraulic pump of simple construction and high capacity and capable of efficient operation at high speed. More particularly the construction provides for varying the capacity of the pump by varying the eccentricity of the pump casing relative to the rotor and for controlling the delivery of the pressure fluid to devices adapted to be actuated thereby.

A further object of the invention is to provide a pump having a rotor equipped with inlet and discharge valves and vanes or blades working in a casing including a cylindrical member which is free to revolve with the rotor during the working cycle of the pump and is adapted to be shifted relative to the axis of the rotor to vary the pump delivery.

A further object of the invention is to provide a rotary pump of the character above described having a priming means driven from the rotor shaft.

The invention further consists in the several features hereinafter set forth and more particularly defined by claims at the conclusion hereof.

In the drawings Fig. 1 is a vertical, sectional view through a pump embodying the invention, taken on the line 1—1 of Fig. 2;

Fig. 2 is a horizontal sectional view through the pump taken along the line 2—2 of Fig. 1;

Fig. 3 is a detail sectional view of the delivery control valve taken along the line 3—3 of Fig. 1, showing the parts in one position;

Fig. 4 is a view similar to Fig. 3, on line 4—4 of Fig. 1 showing the parts in another position;

Fig. 5 is a transverse sectional view through the pump taken on the line 5—5 of Fig. 2;

Fig. 6 is a view similar to Fig. 5 showing the parts in another position.

Referring to the drawings, the pump includes a sectional casing or housing comprising the end sections 7 and 8 and the intermediate section 9, adjacent sections having interfitting end engagement with each other and all the sections clamped together by four

through bolts 10 which have been omitted from Fig. 1 for the sake of clearness.

The rotor 11 has a shaft portion 12 journaled in a ball bearing journal 13 mounted in the inner wall 14 of the section 7 and a shaft portion 15 journaled in a ball bearing journal 16 mounted in an end wall 9' of the casing section 9.

The rotor 11 has a main cylindrical body portion 17 to which end plates 18 are secured as by screws 19 forming the sides of the pump casing which is completed by a cylindrical member or ring 20 whose ends have just a working fit with the plates 18 whereby said member 20 may be moved relative to the axis of the rotor.

The body of the rotor is provided with radially disposed inlet ports or passages 21 communicating with an axially extending inlet bore or passage 22 in the shaft portion 12 and with sets of radially disposed discharge passages 24 communicating with an axially extending discharge bore or passage 25.

Passage of the fluid from the inlet passages 21 to the space 26 between the body of the rotor and the ring 20 is controlled by any suitable form of check valves, but I prefer the ball valves 27, seatable against the outer ends of the ports or passages 21 and mounted in the recesses 28 formed in the body and limited in their outward movement by the apertured screw caps 29.

Passage of the fluid to the sets of discharge passages 24 is in each instance controlled by another check valve which preferably is a ball valve 30 working in the enlarged recess 31 in the body and seating against the seat ring 32 in threaded engagement with the body.

These check valves may be normally held to their seats by the usual springs, but as I have found they are not necessary to the satisfactory operation of the pump and unnecessarily complicate it and are liable to get out of order, the same have not been shown.

A series of longitudinally extending vane-guiding-and-carrying slots 33 are cut in the rotor body and extend across from one end plate to the other. These slots are not radially disposed with reference to the axis of 100

the rotor but are offset to one side thereof and a vane or blade 35 is slidably mounted in each of these slots with a nice working fit and have curved edges 36 formed to conform 5 to the curvature of the inner surface of the ring 20 against which they are constantly urged by a plurality of springs 37 bearing at one of their ends against the flat rear faces 38 of the blades and each mounted at their 10 other end in recesses or holes 39 in the rotor, these holes being provided at the ends and central portion of the rotor so as to clear the valve recesses.

The shaft portion 12 has a gear 40 keyed 15 thereto and spaced from the adjacent end plate 18 by a ring 41 and meshing with a gear 42 on a shaft 43 suitably journaled in ball bearings 44 mounted in the casing section 7 and having an extension 45 for direct or indirect connection with an electric motor or other suitable prime mover.

The inner races of the journal 13 are secured to the rotor against a shoulder 46 by a spacer ring 47, eccentric 48 and a clamping 25 nut 49 and the inner race of the journal 16 is secured against a shoulder 50 by a nut 51 and lock washer 52.

The passage 24 in the shaft portion 15 discharges into a conduit or passage 53 in the 30 casing section 8 and for sealing the bore 54 through which said shaft projects I provide a hardened steel ring 55 seating against the shoulder 56 of the rotor shaft, a ring 57 of hard fibre abutting the ring 55 and having 35 a bevelled edge 58 in abutting engagement with the similarly bevelled edge of a bronze ring 59 which has a close fit in the bore 54, a spring 60 being interposed between the outer end of the ring 86 and the stationary casing 40 and acting to hold these rings in abutting engagement with each other.

The cylindrical member or ring 20 forming the barrel of the pump casing has an annular groove 61 formed therein and a sectional 45 roller bearing 62 is disposed in this groove and within the confines of a ring-shaped support 63 which is provided with a forked lower end 64 receiving a pivot pin or bolt 65 also extending through a lug 66 in the casing 50 section 9, suitable provision being made for holding this support 63 in different positions of angular adjustment relative to the axis of the rotor, as hereinafter described.

The space 67 within the end casing section 55 7 constitutes a reservoir which may be supplied with oil through the filling opening 68 or a return from the system and also from a pump driven from the rotor and incorporated in the casing section 7 and here shown as a 60 plunger 69 working in the bore 70, formed in the casing 7, and reciprocated by the eccentric or cam 48 against which it is held by a spring 71 mounted at one end in a bore of said plunger and engaging a plug 72 at its 65 other end, said pump including a ball check

inlet valve 73 limited in its movement by a stop pin 74 and a ball check discharge valve 75 limited in its movement by a stop pin 76, the valve 73 controlling the passage of fluid from the interior 77 of the casing 9 into the pump casing 78 and the valve 75 its discharge to a pipe 79 communicating with the reservoir 67.

The interior 77 of the casing section 9 is also through openings 80 in communication with the interior 81 of the casing section 8 so that any slight leakage of the working fluid through the joints previously described finds its way into the interior 77 from which it is drawn out by the priming pump above described and discharged into the reservoir 67.

With the above construction and referring more particularly to Figs. 3 and 4 and assuming clockwise rotation of the rotor, during the time the vanes are passing through the lower half of their revolution the space 26 between the body of the rotor and the ring 20 is gradually enlarged and suction takes place, the balls 27 rising off their seats during this time to admit the fluid from passage 22 and ports 21 into said space, and as said vanes pass through the upper half of their revolution the space between them and the rotor and ring 20 gradually contracts and the fluid is discharged past the ball valves 30 into the discharge line 25 and at the desired working pressure. It is, however, to be noted that the vanes 35 do not revolve relative to the ring 20 but, by reason of the angular disposition of said vanes relative to said ring and the fact that the roller bearings 62 offer no appreciable resistance to its turning and its ends work on the end plates, said ring revolves with the vanes but owing to the fact that the support or guide for the ring is eccentrically disposed relative to the axis of the rotor, the blades or vanes 35 move in and out and co-operate with the rotor and barrel to accomplish the pumping action, as above described.

Since the travel of the blades in and out relative to the rotor is dependent upon the eccentricity of the ring 20 relative to the rotor, it will be noted that decreasing this eccentricity reduces the volumes of liquid handled between the blades and finally at zero eccentricity or when the center of the revolution of the ring 20 coincides with the axis of rotation of the shaft, no displacement by the rotor and no reciprocating movement of the blades takes place and no liquid will be pumped. Furthermore, it will be noted that in this device the rotor with its vanes and the ring 20 provides a series of radially disposed pumping chambers in which the pumping cycle successively takes place as the rotor revolves to discharge the fluid into the discharge passages 25 and 53 and at high speeds a great volume of fluid may be readily and efficiently handled in this manner at pressures suitable for working needs.

Any suitable means may be used for adjusting and maintaining the support 63 in the desired angular adjustment and as one example I show said support 63 provided with 5 a stud 82 opposite its pivot 65 and projecting upwardly through an opening 83 into the path of a manually adjustable screw 84 in threaded engagement with a lug in the casing section 9, the reaction of the moving parts 10 tending to hold the stud 82 against the screw, which may be turned in or out in its mounting in the casing to respectively swing said support toward the left or permit its return movement toward the right and thus vary the 15 eccentricity of the pump cylinder 20.

This action furnishes an almost steady flow of pressure fluid to the discharge passage 53 and in case the pressure of this fluid exceeds the desired working pressure a relief valve 20 85, normally held to its seat by a spring 85' over a by-pass 86, opens to permit the fluid to flow by way of port 86' into the interior 81 and thence by way of the chamber 77 to the priming pump.

25 Where the flow of pressure fluid is used to drive reciprocating elements, the reversing valve structure shown in Figs. 5 and 6 controls the delivery of the pump and includes a cage 87 mounted in the casing section 8 and 30 housing a rotary cylindrical plug valve 88 whose inner end 89 is journalled in a bore 90 in the section 8 and whose outer end portion works against a sealing ring 91 in the cage 87 and has an exteriorly disposed shaft projection 92 for manual or power control.

This valve 88 has a centrally disposed inlet 93 communicating with the discharge 53 and provided with radially disposed ports 94 and 95 and a by-pass groove 96.

40 Where the device is used to control the flow of pressure fluid to and from a main cylinder the registering ports 97, 97' lead to the main cylinder and ports 98, 98' conduct the return from said cylinder and ports 99, 99' are connected by a return passage 100 with the 45 reserve reservoir 67, said passage including a pipe 101 whose ends are in sealing contact with the adjacent parts of the casing sections.

With the above construction, when the 50 valve is turned to the position shown in Fig. 5 the pressure fluid delivered by the pump passes through the passage 93, ports 94, 97', 97 to one side of the main cylinder to move the piston therein in one direction while the 55 fluid on the other side of the piston is exhausting through ports 98, 98', groove 96, through ports 99', 99 to passage 100. When the valve is turned to the position shown in Fig. 6 the pressure fluid delivered by the 60 pump passes through the passage 93, ports 95, 98', 98 to the other side of the main cylinder while the fluid is being exhausted from the first side through the ports 97', 97, groove 96, ports 99', 99 to passage 100.

65 Thus the valve structure above described

is associated with the rotary pump to cause the stream of pressure fluid to alternately change its direction and thus produce reciprocation of a piston or other part working in a cylinder connected with the pump.

I desire it to be understood that this invention is not to be limited to any particular form or arrangement of parts except insofar as such limitations are included in the claims.

What I claim as my invention is:

1. In a hydraulic pump, the combination of a rotor having a body portion formed to provide an annular space, a ring member revolving with said rotor and fitting within said space and defining with the sides thereof a chamber, reciprocating blades mounted in the body of the rotor and working within said annular space and defining with said rotor and ring member a plurality of pumping compartments, valve-controlled inlet and discharge passages in the rotor communicating with said compartments, and adjustable means in which said ring member is freely journalled for varying the position of said ring member relative to the axis of rotation of the rotor to vary the output of the pump.

2. In a hydraulic pump, the combination of a rotor having inlet and discharge passages formed therein, valves mounted in said rotor and controlling said passages, a casing member revolvable with but eccentrically movable relative to the rotor and defining therewith a pumping space, and reciprocating blades working in the rotor and against said member and dividing said space into a plurality of pumping compartments, said blades being offset relative to the axis of the rotor and acting to revolve said member with the rotor during the pumping cycle.

3. In a hydraulic pump, the combination of a housing having a supply chamber formed in one end and a discharge passage formed in the other end, a rotor journalled in said housing with hollow shaft portions respectively communicating with said supply chamber and said discharge passage, means for sealing the revolving connection between the discharge end of the rotor and that portion of the casing containing said discharge passage, said rotor having a cylindrical body portion provided with flanged ends, a ring member having working contact with said flanged ends and surrounding said body portion of said rotor and defining therewith a working space, blades slidably mounted in the rotor and engaging said ring and offset relative to the axis of the rotor and dividing said space into a plurality of pumping chambers, valve-controlled inlet passages leading from the inlet passage of said shaft to said chambers, valve-controlled discharge passages leading from said chambers to the discharge passage in the shaft of the rotor, and means for varying the eccentricity of said ring member relative to the axis of rotation

- of the rotor to vary the capacity of the pump.
4. In a hydraulic pump, the combination of a housing having a supply chamber formed in one end and a discharge passage formed in 5 the other end, a rotor journalled in said housing with hollow shaft portions respectively communicating with said supply chamber and said discharge passage, means for sealing the revolving connection between the discharge end of the rotor and that portion of 10 the casing containing said discharge passage, said rotor having a cylindrical body portion provided with flanged ends, a ring member having working contact with said flanged 15 ends and surrounding said body portion of said rotor and defining therewith a working space, blades slidably mounted in the rotor and engaging said ring and offset relative to the axis of the rotor and dividing said space 20 into a plurality of pumping chambers, valve-controlled inlet passages leading from the inlet passage of said shaft to said chambers, valve-controlled discharge passages leading from said chambers to the discharge passage 25 in the shaft of the rotor, a pivotal support for said ring member, a roller bearing journalled between said support and said ring member, and manually controlled means for shifting said support to vary the eccentricity of said 30 ring member relative to said rotor to vary the capacity of the pump.
5. In a hydraulic pump, the combination of a sectional casing having an intermediate section and end sections detachably secured 35 together, said end sections having fluid-receiving spaces, a rotor journalled in said casing and having a body portion having flanged sides disposed in said intermediate sections and hollow shaft portions communicating 40 with the fluid-receiving portions of said end sections, a revolvable barrel member working between said flanged sides and surrounding a portion of the rotor, blades slidably mounted in said rotor and working between said 45 flanged sides and in contact with said barrel member and defining with said member and rotor a plurality of pumping compartments, valve-controlled inlet ports connecting one of the hollow shaft portions with 50 said compartments, valve-controlled discharge ports connecting said compartments with the other hollow shaft portion, means for controlling the position of said barrel member relative to the axis of rotation of the 55 rotor to vary the capacity of the pump, a priming pump having its casing formed in one of said casing sections, and having a valve-controlled inlet port communicating with the space in the intermediate section 60 surrounding the rotor and a valve-controlled discharge passage communicating with the fluid-receiving space of one of said end sections, and a reciprocating plunger driven by said 65 rotor.
6. In a hydraulic pump, the combination 70 of a rotor having inlet and discharge passages formed therein, valves controlling said passages, a casing member revolvable with but eccentrically movable relative to the rotor and defining therewith a pumping space, reciprocating blades working in the rotor and against said member and dividing said space into a plurality of pumping compartments, said blades being offset relative to the axis 75 of the rotor and acting to revolve said member with the rotor, a housing in which said rotor is mounted having a supply chamber and a discharge passage, said rotor having a hollow shaft portion connecting said supply chamber with said inlet passages and a hollow shaft portion connecting said discharge passage with said discharge passages, and a control valve in said supply passage provided 80 with a plurality of discharge ports and a return port, and a rotary valve cooperating with said ports to permit the discharge of pressure fluid into either of said ports and the return of fluid from the other of said discharge ports to said return port, said casing having a passage connecting said return 85 port with said supply chamber.
7. In a hydraulic pump, the combination of a housing, of a rotor journalled in said housing having a cylindrical body portion provided with flanged ends and hollow shaft 90 portions, radially disposed passages in said body portion communicating with the passage provided by one of said hollow shaft portions, ball valves controlling the supply of working fluid through said passages, radially disposed passages in said body portion communicating with the passage provided by the other of said hollow shaft portions, ball valves controlling the discharge of pressure fluid to said last-named passages, a ring member 95 revolving with the rotor and defining therewith a pumping space, and reciprocating blades working in the rotor and against said member and dividing said space into a plurality of pumping compartments with which 100 said radially disposed inlet and discharge passages communicate, and means for varying the position of said ring member relative to the axis of rotation of the rotor to vary the capacities of said pumping compartments.
8. In a hydraulic pump, the combination of a casing, a rotor journalled in said casing with inlet and outlet passages formed therein, said rotor having a cylindrical body portion provided with flanged ends, a ring member having working contact with said flanged ends and surrounding said body portion of said rotor and defining therewith a working space, blades slidably mounted in the rotor and engaging said ring and offset relative to the axis of the rotor and dividing said space into a plurality of pumping compartments, a valve for each compartment mounted in the 110 body portion of the rotor for controlling said 115
- 120
- 125
- 130

inlet passages, a valve for each compartment mounted in the body portion of the rotor for controlling said outlet passages, and means forming a journal for said ring member and adjustable angularly to vary the eccentricity of said ring member relative to the axis of rotation of the rotor to vary the capacity of the pump.

In testimony whereof, I affix my signature.
PERCY OLIVER OTT.
